The ornamental design for a medical storage rack for holding sterile surgical instruments, as shown and described.

DESCRIPTION

FIG. 1 is a perspective view of a medical storage rack for holding sterile surgical instruments, showing our new design;

FIG. 2 is a top plan view thereof;

FIG. 3 is a front elevational view thereof;

FIG. 4 is a rear elevational view thereof;

FIG. 5 is a side elevational view thereof;

FIG. 6 is a side elevational view thereof, opposite that shown in FIG. 5; and,

FIG. 7 is a bottom plan view thereof.
